STRUCTURAL JOINT

Nathaniel P. Green, University City, Mo.

Application May 26, 1941, Serial No. 395,122

7 Claims. (Cl. 20—92)

This invention relates to structural joints, and with regard to certain more specific features, to joints which provide end bearings for wooden compression struts and the like.

Among the several objects of the invention may be noted the provision of a structural joint which applies load to struts in end-grain compression, without shear; the provision of a device of the class described which provides for bearing by compression at any of various angles without the necessity for special end cuts upon the struts; and the provision of a device of the class described which is simple in form and application. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention,

Fig. 1 is a front elevation of an angle plate forming part of the invention;

Fig. 2 is a top plan view of Fig. 1;

Fig. 3 is a right-side elevation of Fig. 2;

Fig. 4 is a side elevation of a heel plate viewed from the upper right as shown in solid lines in Fig. 5;

Fig. 5 shows a left-side elevation (in solid lines) of the heel plate of Fig. 4 along with a mating heel plate shown in dotted lines, both located in operating position upon the end of a strut, also shown in dotted lines;

Fig. 6 is a fragmentary side elevation showing one application of the invention to forming certain joints;

Fig. 7 is a diagonal section taken on line 7—7 of Fig. 6;

Fig. 8 is a view similar to Fig. 6 but showing another application; and,

Fig. 9 is a diagonal section taken on line 9—9 of Fig. 7.

Similar reference characters indicate corresponding parts throughout the several views of the drawings.

Wooden structures such as cooling towers require a large number of angularly positioned compression struts which need to be jointed into the structure as economically as possible without sacrifice of strength. The present invention provides an improved form of joint for the purpose.

Referring now more particularly to Figs. 1-3, 55

there is shown in general at numeral 1 an angle plate consisting of a knee socket portion 3 from which extends a pad 5, ribbed for strength as indicated at 7 and 9. A bolt hole 11 is provided through pad 5 in rib 7.

At a right angle to the pad 5 extends a second and longer pad 13, centrally ribbed as indicated at 15 and provided with bolt holes 17 through a boss portion 18. The rib 15 and boss 18 terminate one in the other.

The inner contour of the knee 3 is circular and smooth, as indicated at numerals 19. The radius of curvature is indicated at 21 and the virtual center of curvature at 23.

The rib 15 extends into the circular portions 19 where it takes the form of a flange 25 in which is an arcuate opening 27. The center of the arc of opening 27 is also at 23.

Numerals 29 indicate integral tongues which are mortised into grooves 33 (Fig. 6). These tongues are chamfered as indicated at 34. Figs. 6 and 7 indicate an example of use of the angle plate. For example, in Fig. 6, there is shown a wooden column 31 grooved at 33 for mortising in the tongues 29. A bolt 35 passing through one of the openings 17 serves to hold the pad 13 against the column 31. In Fig. 6 the device is inverted at the right and the short pad 5 is mortised into the upper surface of a wooden beam 37, as indicated at 39. The beam is held up by said pad by connection with a bolt 41 passing through the opening 11. Thus the angle plate 1 holds up the beam 37 but any thrusts thereon which are angled with respect to the plane of the pad 13 will be resisted axially by the column 31, due to the insertion of the tongues 29 into the grooves 33.

Referring now to Figs. 4 and 5, wherein the heel plate is shown, it is to be understood that two heel plates 43 are used at the end of each strut in connection with each angle plate 1 (above described). Each heel plate 43 consists of a flat bearing pad 45 from which extends an arcuate bearing heel 47 having a bolt hole 49 therethrough. At a right angle is located an offset holding pad 51, also having a bolt hole 53 therethrough. The bearing heels are spaced from the edges 52 and 54.

To prepare a strut 55 for application of the heel plates 43, it is only necessary to trim its end off at right angles and drill a hole 59 at a suitable location to be aligned with holes 53. A pair of heel plates is then applied, as indicated at 57, and since the pad portion 45 of each plate has an extension 61, a space 63 is left for the reception between the spaced heels 47 of the

flange 25 on the angle plate 1. This is indicated in Fig. 7, for example.

A bolt 65 passing through the holes 53 holds a pair of the heel plates to the sides of the strut 55 but does not function in shear. A bolt 67 passing through the bolt openings 49 passes freely through the openings 27 in the flange 25. The clearance between the opening 27 and the bolt 67 is ample to permit free movement of the bolt under angling of the strut and also permits of transmitting the load from the end of the strut, by end-grain compression through the flat faces of the pads 45, then by metal contact through the arcuate heels 47, and to the arcuate faces 19. The radius of curvature of the circular faces 47 of the heels 43 is the same as that of the faces 19, being again indicated by numeral 21 with the virtual center of curvature at 23 (see Fig. 4).

Advantages of the invention are that the load is taken in full by end-grain compression so far as the wooden strut 55 is concerned. Variations in the angle of the center line of the strut may be accommodated without special cutting of the end of the struts. The bearing load is supported metal to metal over relatively large areas regardless of the strut angle. The parts are easy to apply and are themselves very simple in form and may consist of malleable castings, forgings or the like.

In Fig. 6 at the lower left is shown a second joint in direct thrust alignment with the joint shown at the upper right. However, since no beam is used at the left of column 31, corresponding to the beam 37, a shorter pad 5 may be used, and to this end the angle plate 1 is shown with a short upper pad 71.

In Fig. 8 is shown at the upper right a joint such as described in connection with the upper-right portion of Fig. 6. In this Figure 8, as well as in Fig. 9, there is shown at the lower left the application of the heel plates 43 to large-size timbers. It will be apparent that the plates are primarily designed for given timber sizes, such as for example 4 x 4 inch timbers (see Fig. 6). Sometimes, longer timber struts are needed but the load is no greater and additional timber section is used simply to prevent buckling. In such cases the same end-grained areas will carry the load. Therefore a timber, such as for example, a 6 x 6 inch timber 74 is trimmed down by lateral notching as indicated at 73 in Figs. 8 and 9. Chamfers 75 prevent interference with adjacent parts.

Fig. 8 also indicates how the center lines of a pair of struts may intersect a given center 71 on the column 31 even though the strut angles are different. This is accomplished by adjusting the relative positions of the angle plates so that the beams such as 37 and 79 will be coaxial. In such case, a pad 81 is placed above the pad 5 for supporting said second beam 79.

It is to be emphasized that neither the bolts 65 nor 67 carry any compression loads, but simply serve to position the heel plates 43 upon the end of the respective strut. The bolts 67 serve to hold the extensions 47 in alignment and to facilitate assembly of the structure during erection.

The invention is particularly applicable to the building of cooling towers and the like where a large number of compression struts are used and which it is desired shall be placed in position with maximum speed and economy of material and labor.

In view of the above, it will be seen that the

several objects of the invention are achieved and other advantageous results attained.

As many changes could be made in the above constructions without departing from the scope 5 of the invention, it is intended that all matter contained in the above description or shown in the accompanying drawings shall be interpreted as illustrative and not in a limiting sense.

I claim:

10. A structural joint comprising an angle plate having a supporting pad, arcuate bearing surfaces upon said plate, a rib on the angle plate having an arcuate opening and located between said arcuate bearing surfaces, a pair of heel plates, each of which has an arcuate bearing portion for engaging said arcuate bearing portions on the angle plate on opposite sides of said rib, each of said heel plates having a flat engaging area for engaging the end-grain of a 20 strut, each heel plate having a side wall having an opening for fastening, means fastening said heel plates to opposite sides of the struts, said arcuate extensions on the heel plates having openings for receiving a bolt which is movable 25 freely in said arcuate opening of said rib in the angle plate.

2. A structural joint comprising an angle plate consisting of a supporting pad, a right-angular member extending therefrom, arcuate bearing surfaces formed on said plate between the pad and extension, a rib attached to the angle plate and separating said bearing surfaces and having an arcuate opening therein, a pair of heel plates, said plates having flat compression areas abutting end-grain area of the end of a strut, arcuate extensions from the heel plate members having openings therethrough and accommodating a bolt, said arcuate extensions abutting the arcuate portions of the angle plates, said arcuate opening in the rib of the angle plate freely accommodating the bolt in the heel plates, and sideward portions on said heel plates engageable with sideward portions of said struts, said sideward portions and strut having coaxial openings for reception of a holding bolt.

3. A structural joint comprising a plate having an angle portion, a knee socket portion at the angle, said socket portion being arcuately formed, a pair of heel plates each of which has an arcuate edge bearing portion for engaging said arcuate form of the knee socket portion, each of said heel plates having a flat engaging area for engaging the end grain of a strut, and each heel plate having a side wall having means for fastening said wall to the strut.

4. A structural joint comprising a plate having an angle portion, a tongue extending from the plate for mortising into a timber, a knee socket portion at the angle, said socket portion being arcuately formed, a pair of heel plates each of which has an arcuate edge bearing portion for engaging said arcuate form of the knee socket portion, each of said heel plates having a flat engaging area for engaging the end grain of a strut, and each heel plate having a side wall with means for fastening said wall to the strut.

5. A structural joint comprising a plate having an angle portion, a knee socket portion at the angle, said socket portion being arcuately formed with an intermediate rib, a pair of heel plates each of which has an arcuate edge bearing portion for engaging said arcuate form of the knee socket portion on opposite sides of said rib, each of said heel plates having a flat en-

gaging area for engaging the end grain of a strut, said heel plate having a side wall, means fastening said heel plates to opposite sides of the struts, said arcuate edge bearing portions on the heel plates respectively having rotary engagement with said arcuate knee socket portion on opposite sides of said rib.

6. A structural joint comprising a plate having an angle portion, a knee socket portion at the angle, said socket portion being arcuately formed with an intermediate rib, said rib having an opening therethrough, a pair of heel plates each of which has an edge bearing portion for engaging said arcuate socket form of the knee socket portion on opposite sides of said rib, each of said heel plates having a flat engaging area perpendicular to its edge for engaging the end grain of a strut, each heel plate having means fastening it to one side of the strut, said arcuate extensions on the heel plates having openings for receiving a bolt, said opening in the rib being large enough to accommodate free movement of said bolt with movement of the heel plates in the socket.

7. A structural joint comprising a plate hav- 25

ing a vertical and a horizontal extension angled for attachment to adjacent structural members, one extension at least having a tongue for mortising into its structural member, and a knee socket portion at the juncture between said angled extensions, said socket portion being arcuately formed with an intermediate rib, said rib having a ridge and an arcuate opening therethrough, a pair of heel plates each of which has an arcuate edge bearing portion for engaging said arcuate socket form of the knee socket portion on opposite sides of said rib, each of said heel plates having a flat engaging area for engaging the end grain of a strut, said flat portions clearing said ridge on the rib, each heel plate having a side wall having an opening for fastening, means fastening said heel plates to opposite sides of the struts, said arcuate extensions on the heel plates having openings for receiving a bolt, said arcuate opening in the rib being large enough to accommodate free movement of said bolt under rotation of the heel plates in the knee socket.
